Application December 24, 1947, Serial No. 793,729

10 Claims. (Cl. 179—100.2)

1

My invention relates to magnetic recorders and has for its principal object the provision of an improved electromagnetic transducer head assembly for use therein.

In one method of magnetic recording, a lengthy magnetizable medium is drawn across an electromagnetic transducer head assembly at uniform linear velocity. The head assembly includes a magnetic core member having an air gap over which the medium passes and which is provided with suitable current conducting exciting elements to produce a magnetic field across the air gap.

During recording operations, current is caused to flow in the exciting elements in accordance with the time variations of an intelligence to produce a time-varying magnetic field in the core in accordance with the value thereof. Since the field fringes at the air gap portion of the core, the lengthy magnetizable medium partakes of this field as it is drawn thereover, and magnetization is imparted to incremental lengths thereof in accordance with the time variations of the intelligence, thus causing variations in the magnetization of said medium along its length in accord with the time variations of the intelligence.

During reproduction, the lengthy magnetizable medium is drawn across a similar head assembly to cause flux in the core portion thereof in accord with the magnetization of the medium at the incremental length thereover. The resultant time-varying flux induces voltage in the coil encircling the core in accord with the time rate of change thereof, which voltage may be amplified and suitably reproduced by a loud speaker or similar device to reproduce the intelligence recorded.

Inasmuch as magnetic recording and reproducing inherently involves the conversion of an intelligence to a time-varying magnetic field during the recording operation, and conversion of a time-varying magnetic flux to an intelligence in the reproducing operation, it is of utmost importance that the mechanism provided for this purpose be free from effects due to stray magnetic fields. Frequently, for example, the transformers used in conjunction with the recording and reproducing apparatus or the induction or other A. C. motors used therein produce stray magnetic fields which operate to produce annoying hum in the audible output of the apparatus. In accordance with my invention, this hum, together with any other disturbances associated with stray magnetic fields, are overcome by suitable balancing means and in a head mechanism that is simple in construction and reliable in operation.

2

Moreover, it is frequently desirable in a magnetic transducer head assembly to provide a mechanism having a large impedance ratio, to the end that the unit may be effectively connected to a high impedance circuit as, for example, the grid-cathode space path of a vacuum tube.

It is, therefore, a general object of the present invention to provide an improved electromagnetic transducer head assembly for a magnetic recorder. 10 A further object of the present invention is to provide an improved electromagnetic transducer head assembly for a magnetic recorder and in which the elements are so disposed as inherently to balance out the effects of any stray magnetic fields.

Further, it is an object of the present invention to provide an improved electromagnetic transducer head assembly for a magnetic recorder in which the impedance of the windings may be 15 selected at will, and in which a simple and readily assembled secondary winding assembly is provided while at the same time, the effects of stray magnetic fields are eliminated.

Still another object of the present invention 20 is to provide an improved electromagnetic transducer head assembly that is efficiently operable in conjunction with high impedance circuits.

Another object of the present invention is to provide an improved magnetic recorder in which apparatus producing stray magnetic fields may 25 be used but without affecting the operation thereof.

My invention further resides in features of construction, combination and arrangement, whereby an improved head assembly for magnetic recorders in which the effects of stray magnetic fields are balanced out and which is of simple construction suitable for mass production, to the end that a unit of maximum utility may be provided.

40 The novel features which I believe to be characteristic of my invention are set forth with particularity in the appended claims. My invention itself, however, both as to its organization and method of operation, together with further objects and advantages thereof will best be understood by reference to the following description taken in connection with the accompanying drawings in which:

Figures 1, 2 and 3 are side elevational, end elevational and top plan views, respectively, of one 45 embodiment of the present invention;

Figure 4 is a fragmentary cross-sectional view through the axis IV—IV of Figure 3, showing the bridge portion and core portion of the assembly of Figure 3;

55 Figure 5 is a cross-sectional view through the

axis V—V of Figure 4, showing the head core member and the disposition of a lengthy magnetizable recording medium passing thereover;

Figure 6 is a schematic circuit diagram of a magnetic recorder and reproducer operably connected to the electromagnetic transducer head of the present invention;

Figures 7 and 8 are top plan and side elevational views, respectively, of a further embodiment of the present invention; and

Figures 9 and 10 are top plan and side elevational views, respectively, of still another embodiment of the present invention.

As may be seen in the views of Figures 1, 2 and 3, the head assembly of the present invention includes a transformer core portion 18 of silicon steel or similar material and which is of rectangular shape having window 20 to define a pair of aligned legs 22 and 24. A coil or winding indicated generally at 26 encircles the core 18; this coil being divided in two portions 26a and 26b having like numbers of turns and which encircle the aligned legs 22 and 24, respectively. Conducting sleeves 28 and 30 are mounted outwardly of the coil 26a and 26b, respectively, and are sustained thereon by the insulating spacers 29 which are mounted about the periphery of the coil 26 as is best seen in Figure 3, and which snugly fit between that coil and the sleeves 28 and 30.

The sleeves 28 and 30 are made of copper or like conducting material and, as seen best in Figure 3, each nearly encircles the corresponding leg, 22 and 24, respectively, sleeve 28 having an arcuate open portion defining the confronting edge portions 28a and 28b, Figure 3; and the sleeve 30 having a similar arcuate open portion defining the confronting edge portions 30a and 30b, Figure 3.

The arcuate open portions of the sleeves 28 and 30 are on the same side of the core 18 and partially face each other. The confronting end portions 28a and 30a are interconnected by the U-shaped conducting member 32 which has a pair of turned-out flanges 32a and 32b for connection to the sleeves 28 and 30, respectively, by soldering or like means. Similarly, the conducting member 34 has turned-in end portions connected to the edge portions 28b and 30b of the sleeves 28 and 30, respectively.

The conducting members 32 and 34 are constructed of copper or like conducting material and extend across a substantial portion of the length of the sleeves 28 and 30, as may be seen in the view of Figure 1, thus defining a low resistance current path in conjunction with the sleeves. As indicated by the dotted lines of Figure 1 and the view of Figure 5, the member 34 is of like length axially of the legs 22 and 24 as is the member 32. At their central portions, the members 32 and 34 define spaced parallel conductors to receive the head core member 36. A conducting bridge 38 extends between the members 32 and 34 and is received in the core 36 to produce flux therein in accord with current flow therethrough.

The construction of the bridge 38, together with the core 36 is best seen in the views of Figures 4 and 5. As seen in the view of Figure 4, the conducting bridge 38 is of rectangular shape and is received at its opposite ends in slots in the members 32 and 34. In order to accomplish a good path for current conduction between the bridge 38 and the members 32 and 34, the bridge 38 is preferably brazed to these members as indicated by the beads 38a and 38b, Figure 3.

As shown in Figure 5, the bridge 38 is rela-

tively thin and is received in a slot 36a of the core 36. This slot also defines the air gap across which a lengthy magnetizable medium 42 is drawn. This core is of substantially rectangular shape with a rounded off top portion 36b, the slot 36a extending from that top portion down approximately to the center of the core 36.

The bridge 38 is positioned relative to the sleeves 28 and 30, and the members 32 and 34 to divide the current path defined thereby into two symmetrical halves. This is seen best in the view of Figure 3.

It will be apparent to those skilled in the art that when current flows through the bridge 38 in direction transverse to the plane of cross-section of Figure 5, a magnetic field is set up about the bridge 38 and results in magnetic flux being developed in core 36 following a closed path such as that generally indicated at 40. Moreover, this current flow produces a magnetic field across the air gap defined by the groove 36a, the intensity of this magnetic field being determined by the reluctance of the magnetic path defined by the core 36, the size of the slot 36a and the intensity of current flow through the bridge 38. Since the core 36 is preferably constructed of iron having a high magnetic permeability, and the slot 36a is narrow, the intensity of the magnetic field across the gap defined by the slot 36a is relatively great, particularly at the end portions thereof adjacent the edge 36b of the core 36.

The upper edge 36b of the core 36 is rounded to receive a lengthy magnetizable recording medium such as, for example, a fine steel wire. A groove or slot 36c, Figures 2 and 3, is formed in this edge of the core and, as shown in Figures 4 and 5, receives the lengthy magnetizable medium 42. The conducting member 32 is provided with a pair of V-shaped notches 32c and 32d, Figure 3, to provide space for the passage of the record medium 42 through the assembly.

In the figures, the medium 42 is shown greatly enlarged to illustrate clearly how it rests on the head core 36. Actually, this medium is best made of very fine material, such as, for example, steel wire four mils in diameter. Moreover, the width of the bridge 38 and the slot 36a in which it is received is greatly exaggerated to illustrate clearly the arrangement of the parts, and in an actual embodiment, this width is preferably made very small such as, for example, less than one mil.

The operation of the structure of Figures 1 to 5 may best be understood by the schematic diagram of Figure 6. For purposes of identification, like elements on the structure of Figures 1 to 5 are identified with like numbers on Figure 6. As indicated in Figure 6, the coil 26 is connected to the magnetic recording and reproducing unit 44. This unit contains elements to convert intelligence such as sound, for example, to a time-varying voltage which is impressed across the coil 26. During the reproducing operation, the recorder and reproducer 44 includes elements to convert the time-varying voltage in coil 26 to the original intelligence such as, for example, sound.

It will be observed that as the conducting path including the recorder 44 and the coil 26 is traversed in a single direction as, for example, the path indicated by the arrows 46; the leg 22 of core 18 is encircled in an opposite direction to the leg 24. Accordingly, current flow in coil 26 associated with voltage produced by the recorder 44 causes oppositely directed fluxes to be developed in the core portions 26a and 26b as indi-

cated by the arrows 48 and 50, respectively. Since these fluxes or magnetomotive forces are in like direction and additive relationship as the core 18 is traversed, the total flux produced therein is that associated with the combined operation of these coils. The sleeves 28 and 30, which are represented by corresponding turns on the legs 22 and 24 of the core 18, also link the flux produced by current flow through the coil 26. Voltages are induced in these sleeves tending to cause current flow therethrough, this current flow being in direction to pass through the bridge 38, represented by a resistance, in Figure 6, in like direction as indicated by the arrows 52, 54 and 56, Figure 6. The bridge 38 is indicated by a resistance, since it is of relatively great resistance as compared to the resistance of the other portions of the circuit. Current flow in the bridge member 38 produces magnetizing magnetomotive force as is shown in Figure 5.

It will be observed that stray flux such as, for example, might be directed in direction of the arrow 58, Figure 1, has no effect on the voltage produced across the bridge member 38, even though the direction of the flux 58 has a component in alignment with the windings 26 and the sleeves 28 and 30. Such flux produces like fluxes in the opposite legs 22 and 24 of the core 18. However, these fluxes produce additive voltages in the sleeves 28 and 30 as the latter are traversed through the path including sleeve 28, member 32, sleeve 30 and member 34. However, since these sleeves are of like resistance and impedance, and the bridge 38 is symmetrically disposed relative to members 32 and 34, there is no tendency for a voltage to be produced across the bridge member 38 as a consequence of this flux.

Moreover, when the unit is used as a pick-up to produce voltage for application to the recorder 44, flux such as that of arrow 58 produces no effect on the output voltage, inasmuch as it is of like direction with respect to the sleeves 28 and 30, and the conducting paths defined therewith by the members 32 and 34, and, in addition, the coil 26 is responsive only to fluxes in opposite direction through the core members 22 and 24. Thus, the head of the present invention is not influenced by the presence of stray fields, and such fields can produce no annoying hum or other effects on the operation of the complete unit.

In one application of the head assembly of the present invention, the magnetic recorder may include a power transformer to supply the necessary operating voltages for tubes and other equipment, and induction drive motor to impart linear velocity to the lengthy magnetizable medium. Although both of these have some tendency to produce stray fields, and hence induce hum in the reproduced output intelligence, they may be mounted with assurance that no effect will be produced on the operation of the unit if the head assembly of the present invention is employed.

Figures 7 and 8 are top plan and side elevation views, respectively, of an alternative embodiment of the present invention. As indicated in these views, two core members, 118 and 118a, each like the core member 18, Figure 1, are provided and are sustained in spaced relationship relative to each other by suitable mounting arms 119. A coil 126 encircles the legs of core 118, and a coil 126a encircles the legs of core 118a. Sleeves 128, 130, 128a and 130a encircle the coils

126 and 126a in like fashion as do the sleeves 28 and 30, Figure 3. Sleeves 128 and 130 are held in position by the insulating spacers 129, and sleeves 128a and 130a are held in place by the insulating spacers 129a. Each sleeve has an open arcuate portion facing the space between cores 118 and 118a.

The sleeves 128, 130, 128a and 130a are connected by the conducting members 134, 132, 134a and 132a, which are of construction similar to the conducting members 32 and 34, Figure 3, except that they are shaped to provide suitable mounting flanges for connection by soldering or like means to the sleeves 128, 130, 130a and 128a. A head core member 136, like the core member 36, Figure 3, is nested in the space defined by the members 134 and 134a and is provided with a suitable groove to receive the conducting bridge 138.

The core 136 is like the core 36 in that it has a groove 136a at its top surface to receive a lengthy magnetizable medium and receive the bridge 138 in a suitable slot to cause a magnetic field to operate upon an incremental length of the medium disposed in the slot 136a in accord with the current flow through the bridge 138.

It will be apparent to those skilled in the art that the unit of Figures 7 and 8 operates in like fashion as the unit of Figures 1 to 5. However, the current paths through the bridge 138, Figure 7, link two legs 122 and 122a or 124 and 124a, whereas the current paths through the bridge 38, Figure 3, link only a single leg 22 or 24.

The coils 126 and 126a which encircle the legs 35 of the cores 118 and 118a are wound in like fashion as the coil 26, Figure 3. These coils are connected in additive series relationship for connection to a magnetic recorder and reproducer in the manner indicated in Figure 6 so that the 40 total voltage applied thereto is the combined voltage induced in coils 126 and 126a during the reproducing operation and the voltage of the recorder is impressed across the combined series of coils during recording. Since the bridge 138 is 45 disposed to divide the circuit of the sleeves 128, 130, 128a and 130a into two symmetrical halves, the unit is hum-bucking in both the primary and secondary circuits, and no voltages are induced in the unit by stray magnetic fields.

The connection of the coils 126 and 126a is such that upon current flow therethrough, flux is produced in one direction in legs 122 and 122a and in the opposite direction in legs 124 and 124a.

The structure of Figures 9 and 10 is like that of Figures 7 and 8, except that the coils 128, 130, 130a and 128a are connected in a parallel connection in which the voltage produced in each coil is impressed across the common bridge 138.

This is accomplished by the criss-cross conducting members 232 and 233 and 232a and 233a. These members may be seen in side view in Figure 10.

The structure of Figures 9 and 10 provides an 65 increased impedance ratio between the primary and secondary windings, since the net effect of the sleeves 128, 130, 130a and 128a in that structure is to produce a single-turn secondary.

Elimination of the effects of stray fields in the 70 apparatus of Figures 7 to 10 is further improved by the fact that the head core 136 is nested between the transformer cores 118 and 118a.

In the foregoing specification and in the appended claims I have defined the head core 36 75 as having an air gap 38 to receive or to be trav-

ersed by the medium. By this expression I intend to include construction such as that of Figure 5 where the air gap flux actually passing through the medium is fringing or leakage flux as distinguished from the direct flux passing in a straight line across the air gap.

While I have shown particular embodiments of my invention, it will, of course, be understood that I do not wish to be limited thereto since many modifications, both in the circuit arrangements and in the structures disclosed, may be made without departing from the spirit and scope of my invention. I, of course, contemplate by the appended claims to cover any such modifications as fall within the true spirit and scope of my invention.

I claim as my invention:

1. An electromagnetic transducer head assembly including at least one core having a pair of aligned legs, means for producing oppositely directed magnetic fields on said legs, a conducting sleeve partially encircling each of said legs, spaced conducting members joining the open ends of the sleeves, a conducting bridge electrically interconnecting said conducting members to form parallel conductive circuits, and a magnetic core member substantially encircling said bridge and having a non-magnetic gap across which a lengthy magnetizable medium may be drawn.

2. An electromagnetic head assembly including a rectangular core having an opening therethrough to define a pair of aligned legs, means for producing oppositely directed magnetic fields on said legs, a conducting sleeve partially encircling each of said legs, spaced conducting members electrically interconnecting the sleeves in series circuit relationship, a conducting bridge electrically interconnecting said members, and a magnetic core member substantially encircling said bridge and having a non-magnetic gap across which a lengthy magnetizable medium may be drawn.

3. An electromagnetic transducer head assembly including a core having a pair of aligned legs, means for producing oppositely directed magnetic fields on said legs, a conducting sleeve partially encircling each of said legs, conducting members electrically interconnecting the sleeves, a conductor electrically interconnecting said conducting members, and a magnetic core member substantially encircling said conductor and having a non-magnetic gap across which a lengthy magnetizable medium may be drawn.

4. An electromagnetic transducer head assembly including a core having a pair of aligned legs, means for producing oppositely directed magnetic fields on said legs, a pair of conducting sleeves substantially encircling said legs and having open portions facing on a common side of said core, a first conducting member connecting the edges of said sleeves closest to each other, a second conducting member in spaced relationship with said first conducting member and connecting the edges of said sleeves most remote from each other, a core member defining a head for said transducer disposed between said conducting members and having a non-magnetic gap across which a lengthy magnetizable medium may traverse and means including a conducting bridge symmetrically positioned relative to said sleeves and electrically connecting said conducting members, said bridge being substantially encircled by said core to produce a magnetic field across said gap upon current flow therethrough.

5. An electromagnetic transducer head assembly including a core having a pair of aligned legs, means for producing oppositely directed magnetic fields on said legs, a pair of conducting sleeves substantially encircling said legs and having open portions facing on a common side of said core, a conducting member connecting the edges of said sleeves closest to each other, a second conducting member in spaced relationship with said first conducting member and connecting the edges of said sleeves most remote from each other, a core member defining a head for said transducer disposed between said conducting members and having a non-magnetic gap across which a lengthy magnetizable medium may be drawn and a conducting bridge symmetrically positioned relative to said sleeves and extending therebetween, said bridge being encircled by said head core to produce a magnetic field across said gap upon current flow therethrough.

6. An electromagnetic transducer head assembly including a rectangular core having an opening therethrough defining a pair of aligned legs, means for producing oppositely directed magnetic fields on said legs, a pair of conducting sleeves substantially encircling said legs and having open portions facing on a common side of said core, a first conducting member connecting the edges of said sleeves closest to each other, a second conducting member in spaced relationship with said first conducting member and connecting the edges of said sleeves most remote from each other, a core member defining a head for said transducer disposed between said conducting members, said head core member having a non-magnetic gap across which a lengthy magnetizable medium may be drawn, and a conducting bridge encircled by said core symmetrically positioned relative to said sleeves and electrically connecting said conductors to produce a magnetic field across said gap upon current flow therethrough.

7. An electromagnetic transducer head assembly including a rectangular core having an opening therethrough defining a pair of aligned legs, means for producing oppositely directed magnetic fields on said legs, a pair of conducting sleeves substantially encircling said legs and having open portions facing on a common side of said core, a first conducting member connecting the edges of said sleeves closest to each other and attached thereto along a substantial portion of the axial length thereof, a second conducting member in spaced relationship with said first conducting member and connecting the edges of said sleeves most remote from each other and attached thereto along a substantial portion of the axial length thereof, a core member defining a head for said transducer of substantially rectangular shape disposed between said conducting members, said head core member having one edge thereof slotted to receive a lengthy magnetizable medium and having a lengthy slot extending inwardly from said edge, and a conducting bridge symmetrically positioned relative to said sleeves and connecting said conductors through said slot of said head core member.

8. An electromagnetic transducer head assembly including a pair of spaced cores each having two aligned legs, windings encircling the flux paths defined by said cores to produce fluxes traversing two of said legs in one direction and the other two of said legs in opposite direction upon current flow through said windings, con-

ducting sleeves substantially encircling each of said legs and having open portions facing the space between said cores, conducting members attached to the edge portions of said sleeves and defining a series current path therewith encircling each of said legs in a common direction, a core member defining a head for said transducer having a non-magnetic gap to be traversed by a lengthy magnetizable medium, and means including a bridge of electrical conducting material connecting opposite portions of said conducting members to define a pair of symmetrical loops therewith, said bridge being electrically connected with and substantially encircled by said head core to cause a magnetic field across said gap in accord with the current flow therein.

9. A head assembly for a magnetic recorder including a pair of spaced cores each having two aligned legs, windings encircling the flux paths defined by said cores to produce fluxes traversing two of said legs in one direction and the other two of said legs in the opposite direction, conducting sleeves substantially encircling said legs and having open portions facing the space defined by said cores, a core member defining a head for said transducer nested between said

cores and having a non-magnetic gap across which a lengthy magnetizable medium may be drawn, a conducting member electrically connected with said head core member and encircled thereby to cause an electromagnetic field across said gap in accord with current flow in said conducting member, and conducting elements connecting the edges of said sleeves to said conducting member, said elements defining at least two physically symmetrical loops in conjunction with said conducting member.

10. An electromagnetic transducer head assembly including at least one core having a pair of aligned legs, means for producing oppositely directed magnetic fields along said legs, conducting sleeves partially encircling each of said legs, spaced conducting members electrically interconnecting said sleeves into a circuit, conducting bridge means interconnecting said members, and a core member substantially encircling said bridge defining a head for said transducer having a gap therein across which a lengthy magnetizable medium may be drawn.

DAVID E. WIEGAND.
